UNITED STATES PATENT OFFICE.

THEOPHILUS R. HYDE, JR., OF WATERBURY, CONNECTICUT, ASSIGNOR
TO SCOVILL MANUFACTURING COMPANY, OF WATERBURY, CONNECTICUT, A CORPORATION OF CONNECTICUT.

BUTTON-FASTENER.

SPECIFICATION forming part of Letters Patent No. 772,280, dated October 11, 1904.

Application filed August 9, 1904. Serial No. 220,100. (No model.)

To all whom it may concern.

Be it known that I, THEOPHILUS R. HYDE, Jr., a citizen of the United States, residing at Waterbury, in the county of New Haven and State of Connecticut, have invented a certain new and useful Improvement in Button-Fasteners, of which the following is a full, clear, and exact description.

A metallic fastening device for use in fastening buttons to garments and for other purposes and composed of a head of approximately the outline of the letter **S** and having a prong projecting at right angles therefrom at each terminal has heretofore been devised, and similar "pronged" fasteners, so called, having their heads variously formed, have also been devised; but in those pronged fasteners of this general character with which I am familiar the pressure necessary to drive the prongs through plies of fabric or other material and clench them about the button or other object to be fastened has a tendency to distort the prongs, owing perhaps to the fact that the prongs lack support on opposite sides.

25 The object of the present invention is to provide a pronged fastener the prongs of which are embraced upon opposite sides by the material of the head.

The invention consists of a button-fastener 30 or pronged fastener having a head of approximately **S** shape with the terminals, containing right-angle prongs, bent back again, so as to locate the prongs between the outer folds and the intermediate cross-fold, and thus support said prongs on both sides, whereby any tendency to distortion of the prongs in the application of the device is resisted.

In the accompanying drawings, illustrating the invention, in the several figures of which like parts are similarly designated, Figure 1 is a perspective view. Fig. 2 is a top plan view. Fig. 3 is a bottom or outside plan view. Fig. 4 shows an ordinary metallic bar-button in cross-section with the fastener applied. Fig. 5 is a perspective view of a capped fastener. Fig. 6 is a top plan view of the fastener of Fig. 5, and Fig. 7 is a bottom or outside view of the capped fastener.

The fastener is made of wire of any suitable cross-section, bent to form a cross-fold 1 and opposite outer folds 2, and the terminals 3 of the wire are turned back between the cross-folds 1 and the outer folds 2, and from these terminals project at right angles the prongs 4. By turning back the terminals 3 toward the center of the device the prongs receive lateral support from the cross-fold 1 and the outer folds 2, which serve to reinforce the prongs sufficiently to resist the distorting tendency of the pressure necessary to drive the prongs through a fabric or other material to which an article is to be fastened and also the pressure necessary to clench the prongs for effecting the fastening.

As illustrated in Fig. 4, one special and 65 large use to which these pronged fasteners are put is in securing bar-buttons to garments. 5 may represent a piece of fabric or a piece of garment, and 6 is a metallic button of common construction having at its base a transverse bar 7 about which the prongs 4 of the fastener are bent in opposite directions to secure the button to the garment.

It will be observed that the head of the fastener formed by the cross-fold 1, outer folds 75 2, and terminals 3 is substantially circular in outline or profile, and thus lends itself very readily to the application of a cap, as indicated at 8 in Figs. 5, 6, and 7, which cap is simply a cup or shell of sheet metal having 80 its flange turned down over the rim or flange of metal formed by the folds outside of and beyond the prongs.

By the construction hereinabove described 85 the prongs are firmly held both on the inner side and outer side diametrically and their liability to displacement greatly reduced and practically wholly overcome.

Since the prongs are substantially equidistant from the center, the outwardly-surrounding metal of the head lends itself very readily to receive a cap of metal or cloth, and thus the fastener may be ornamented or protected in any desired manner.

By the term "button-fastener" herein used 95 I do not mean to limit the invention to fas-

tening on buttons, since its use may be greatly extended, and this is to be understood in connection with the use of that term in the claims.

What I claim is—

- 5 1. A button-fastener, having a head of approximately **S** form in outline, the terminals being returned between the cross-fold and the outer folds and the prongs projecting from the inner ends of said terminals at right angles thereto.
- 10 2. A button-fastener, made of wire, having a head provided with a central cross-fold, outer folds, and terminals on said outer folds returned between the cross-fold and the outer folds and embraced thereby, and prongs projecting at right angles from the ends of said terminals.
- 15 3. A button-fastener, having a head of ap-

proximately **S** form, with the terminals returned between the cross-fold and the outer ²⁰ folds and supported thereby, prongs projecting at right angles from the ends of said terminals, and a cap applied to said head.

4. A button-fastener, having a head of approximate **S** shape and circular in outline, ²⁵ and having the terminals returned between the outer folds and the cross-fold and supported thereby, prongs projecting from the ends of said terminals at right angles thereto, and a cap applied to said head.

In testimony whereof I have hereunto set my hand this 8th day of August, A. D. 1904.

THEOPHILUS R. HYDE, JR.
